HORACE H. BURDETT, OF HOPEDALE, MASSACHUSETTS, ASSIGNOR TO DRAPER CORPORATION, OF HOPEDALE, MASSACHUSETTS, A CORPORATION OF MAINE

REPLENISHING SHUTTLE BOXES

Application filed July 7, 1930. Serial No. 485,914.

This invention relates to shuttle boxes for looms, and is more particularly directed to shuttle boxes of the filling replenishing type.

On replenishment of filling, the old or spent filling between the cloth selvage and the filling carrier or bobbin in the shuttle is liable to be drawn into the shed and produce imperfect cloth, and attempts have been made heretofore to prevent this objectionable condition.

10 The filling leading from the shuttle eye towards the inner end of the shuttle box is also liable to be caught between the side of the shuttle and the inner surface of the front box plate upon call for replenishment, thus leaving a length of spent filling to be carried into the shed on a subsequent pick of the shuttle. It is desirable to line the front box plate with a friction material, such as leather or the like, but where this has been attempted heretofore,

15 20 the filling between the shuttle eye and inner end of the shuttle box has clung to the friction material and emphasized the liability of weaving defective cloth.

An important feature of the present invention consists of a shuttle box of the replenishing type having a front box plate of novel construction whereby the objectionable conditions existing heretofore are overcome and the weaving of perfect cloth made possible.

25 30 In accordance with the present invention the front box plate is provided with a longitudinally extending slot in line with the longitudinal thread groove in the side of a boxed shuttle and open at its inner end, that on call for replenishment the old filling end may be withdrawn freely from the shuttle box throughout its entire length.

Another novel feature of the invention consists of a front box plate having a slot extending longitudinally thereof and dividing the box plate into a lower anchoring member and a shorter upper member supported solely by the anchoring member at the outer portion thereof with the result that the first impact of incoming shuttle is resisted by the rigid anchoring member below the thread groove in the shuttle and thereafter by the shorter upper member as the shuttle enters more fully into the shuttle box.

35 40 45 50 55 60 65 70 75 80 85 90 95 100 Since the inner end of the shorter upper

member is unsupported except at the outer portion of the anchoring member, the checking action of the shorter upper member may be made resilient to some degree and both of said members may be faced with leather or other friction material by virtue of the fact the longitudinal slot in the front box plate coincides or is in line with the longitudinal thread groove in the boxed shuttle thus providing a space in the shuttle thread groove and open slot of the box plate in which the thread will naturally rest with no tendency to drop between the contacting side of the shuttle and inner face of the anchoring member.

The invention and other novel features thereof in addition to the above will best be made clear from the following description and accompanying drawings of one good practical form thereof.

In the drawings:—

Fig. 1 is a plan view of a replenishing shuttle box containing the present invention, parts of the lay being broken away;

Fig. 2 is a front view thereof;

Fig. 3 is a perspective view of the front box plate detached;

Fig. 4 is an enlarged end view of the front box plate looking in the direction of the arrow of Fig. 3; and

Fig. 5 is an enlarged cross-section on the line 5—5 of Fig. 2.

The lay 1 may be of the usual character and be provided at its outer end with a replenishing shuttle box 2, the latter having the usual bottom opening 3 for the passage of the ejected filling carrier or bobbin during replenishing of filling.

In accordance with the present invention the front box plate shown to be detached in Fig. 3 has a longitudinally extending slot 4 which is in line with the usual shuttle groove 5 of a boxed shuttle. The slot 4 in the box plate is closed at its outer end as at 6 and extends longitudinally and substantially central of the box plate towards the inner end of the latter, thus dividing the box plate into an anchoring member 7 and upper member 8, the inner end 9 of which terminates short of the inner end of the shuttle box as more clearly indicated in Figs. 1 and 2.

The anchoring member 7 has lug portions 10 and 11, preferably one at each end by which the anchoring member is secured to the lay by means of bolts 12 and 13, and in 5 order to provide for proper adjustment of the anchoring member the lugs 10 and 11 are provided with slots through which the bolts 12 and 13 pass.

The outer end portion of the slot 4 is enlarged at 14 to provide an entrance for the now well known cutter and clamp for parting the filling adjacent the shuttle eye and clamping it for outward movement by the parter and clamp as the latter moves front- 10 wardly. It will not be necessary to herein describe the parter and clamp as the details of these features form no part of the present invention, which is more particularly directed to the front box plate and its novel 15 construction.

In the construction of the shuttle box heretofore devised there has always been the danger of the filling being clamped between the side of the shuttle and the inner surface 25 of the front box plate and especially will this occur on the filling overthrow or balloon as the shuttle comes to rest. In the present construction of the front box plate, however, the longitudinal slot which divides the 30 front box plate into the anchoring member and upper member and wherein the upper member is shorter than the anchoring member the liability of filling being caught between the shuttle and front box plate is en- 35 tirely overcome, since the space afforded by the longitudinal slot in the box plate and the longitudinal thread groove in the side of the shuttle provides an unobstructed opening in which the filling may rest.

40 Inasmuch as the upper member 8 is supported solely by the anchoring member at its outer portion, the inner end of the upper member is free and provides a space between the end thereof and the end of the shuttle box 45 in which any overthrow or ballooning of thread may escape without entering between the shuttle and box plate.

As hereinbefore noted the anchoring member of the box plate is longer than the upper 50 member and said anchoring member extends substantially the full length of the shuttle box with the result that the rigid anchoring member will first take the impact of the incoming shuttle below the thread groove as it 55 enters the shuttle box and thereafter the upper member will act upon the shuttle as it passes to picking position.

It may be advisable in some cases to strengthen the connection between the outer 60 end portion of the anchoring member and the upper member and this may be readily effected by the metal reenforced member 15 as indicated in Fig. 3.

Heretofore it has not been feasible or practical to line the front box plate with a fric-

tion material owing to the liability of the filling being caught by the frictional material and thus emphasize the objections heretofore existing in the filling being trapped between the shuttle and inner face of the box 70 plate, but with the construction of the front box plate as hereinbefore described where the upper member is shorter than the anchoring member to provide an open ended slot, it is possible to line both the anchoring member and the upper member of the front box plate with the frictional material, such for instance as leather, and in the present instance of the invention the leather lining 16 has two legged portions extending full 75 length of the slot in the front box plate, one of said leg portions 17 being secured to the upper member of the box plate, and the other leg portion 18 being secured to the inner face of the anchoring member. One good practical means of securing the leg portions of the leather or friction material to the anchoring member and upper member, the outer end 80 portions of each leg as at 19 may be turned outwardly towards the front of the box plate and secured to the upper and lower members by screws such as 20. In some cases the friction material may be adhesively secured to the anchoring member and upper member and additional screws such as 21 may be em- 85 ployed.

By the provision of the front box plate with the longitudinally extending slot as described, in line with the thread groove in the side of the shuttle, and the termination of the upper member of the front box plate short of the inner end of the shuttle box, the filling thread of the outgoing carrier or bobbin may be readily withdrawn frontwardly through the slot of the box plate with minimum ten- 90 sion or breakage.

On replenishment of filling the spent filling end may be readily withdrawn front- 100 wardly through the slot of the box plate through the open inner end of the slot and to prevent the old filling end from being carried into the shed or caught upon portions of the front box plate, the anchoring member is provided with an abutment 22 sub- 105 stantially at right angles to the longitudi- 110 nal axis of the shuttle box, the abutment 22 thereby preventing the old filling end from entering the shuttle box or being drawn into the shed during the lay operation.

In replenishing looms where the filling car- 115 rier or bobbin is changed from time to time the end of the new filling is secured at some fixed point such a lug or projection on the hopper or magazine, and in order to prevent the end of the new filling from being carried 120 into the shed the upper member 8 of the front box plate is provided with a thread catcher 23 which will engage the new filling end as the lay moves frontwardly after the first pick movement following replenishment and will 125 130

direct the thread into a holding notch 24 formed in the upper edge portion of the anchoring member. From the construction hereinbefore described it will be apparent that the front box plate having the longitudinal anchoring member and the shorter upper member separated by the slot in the box plate, provides a space between the end 25 of the anchoring member and the end 9 of the upper member in which the thread may overthrow or balloon when the shuttle comes to rest without danger of being caught or trapped between the shuttle and the inner face of the front box plate.

As hereinbefore suggested the upper member 8 of the front box plate is solely supported at the outer end thereof so that a certain amount of resiliency will be permitted the shorter member of the box plate as the shuttle passes to picking position.

It may be desirable at times to form the inner end portion of the anchoring member with an upwardly inclined edge as at 26 which serves to prevent the outgoing filling end from being caught by the securing bolts for the anchoring member.

What is claimed is:

1. A shuttle box for looms having a front plate provided with an open ended thread slot extending longitudinally thereof in line with the thread groove in a boxed shuttle and dividing the front plate into a lower anchoring member and an upper member supported at the outer end of and shorter than the lower anchoring member to provide an upwardly open space above the inner end occurrence of a balloon in the thread as the portion of the anchoring member that on the shuttles come to rest the thread will not be trapped between the shuttle and front plate of the shuttle box.

2. A shuttle box for looms having a front plate provided with an open ended thread slot extending longitudinally thereof in line with the thread groove in a boxed shuttle and dividing the front plate into a lower anchoring member and a shorter upper member solely supported by the anchoring member at the outer end portion thereof, and means for securing the anchoring member of the box plate to the lay that the first impact of the incoming shuttle may be resisted by the anchoring member below the thread groove in the shuttle.

3. A shuttle box for looms having a front plate provided with an open ended thread slot extending longitudinally thereof in line with the thread groove in a boxed shuttle and dividing the front plate into a lower anchoring member and a shorter upper member solely supported by the anchoring member at the outer end portion thereof, a frictional lining having separated leg portions corresponding to the two members and secured thereto, and means for securing the anchoring mem-

ber of the box plate to the lay that the first impact of the incoming shuttle may be resisted by the anchoring member below the thread groove in the shuttle.

4. A shuttle box for looms having a front plate provided with a rigid anchoring member and a substantially resilient upper member shorter than the anchoring member and supported solely by the anchoring member at the outer portion thereof that the first impact of the incoming shuttle may be resisted by the anchoring member and thereafter by the resilient upper member of the front plate as the shuttle moves to picking position.

5. A shuttle box for looms having a front plate provided with a rigid anchoring member and a substantially resilient upper member shorter than the anchoring member and supported solely by the anchoring member at the outer portion thereof that the first impact of the incoming shuttle may be resisted by the anchoring member and thereafter by the resilient upper member of the front plate as the shuttle moves to picking position, and a lining of friction material having leg portions secured upon the inner surfaces of the two members.

6. A front box plate provided with a longitudinally extending slot open at its inner end, a rigid anchoring member below said longitudinally extending slot to take the first impact of the shuttle as it enters the shuttle box and an upper member shorter than the anchoring member above said longitudinal slot and supported at the outer end of the anchoring member beyond the outer end of the longitudinal slot.

7. A front box plate provided with a longitudinally extending slot open at its inner end, an anchoring member below said longitudinally extending slot, and an upper member shorter than the anchoring member and supported solely by the anchoring member at the outer end portion thereof.

8. A front box plate having a longitudinally extending slot in line with the thread groove of a boxed shuttle, an anchoring member below the longitudinally extending slot and a resilient upper member shorter than the anchoring member and the inner end of which terminates between the ends of the anchoring member.

9. A front box plate having a central longitudinal slot in line with the thread groove in a boxed shuttle and open at its inner end, said slot dividing the front box plate into a lower anchoring member and an upper member of less length than the anchoring member and having its free end terminating short of the inner end of the shuttle box.

10. A front box plate having a central longitudinal slot in line with the thread groove in a boxed shuttle and dividing the front plate into an anchoring member and a shorter

upper member supported solely by the outer portion of the anchoring member that the latter may resist the first impact of the shuttle as it enters the shuttle box and upper member may thereafter engage the shuttle and flex under the shuttle impact.

5 In testimony whereof, I have signed my name to this specification.
